DRAWBAR

John S. Keen, Philadelphia, Pa., Allen Wallace, Moorestown, N. J., and Edward O. Elliott, Jenkintown, Pa.

Application January 28, 1933, Serial No. 653,954

6 Claims. (Cl. 213—3)

This invention relates generally to a locomotive and tender draw bar and an improved combination of elements therewith, and more particularly to an improved draw bar of the flexible safety type adapted to maintain a fixed relation between the locomotive and tender.

Large present day locomotives are exceedingly hard to counterbalance on account of not only the revolving parts but also the reciprocating weights, and while the counterbalancing for such a locomotive forms no part of the present invention yet it is important to understand that one of the characteristics of the revolving and reciprocating weights is that there is often too much longitudinal vibration of the locomotive for the best performance. This vibration is materially lessened if the mass of the locomotive is larger and heavier. In order to increase the mass it is desirable to attach the tender more rigidly to the locomotive than is the practice at present, thereby considerably increasing the total mass and reducing the effects of longitudinal vibration.

However, in attempting to combine the mass of the tender with that of the locomotive by means of a rigid connection between the same it becomes apparent that a very strong draw bar construction must be provided. Such a construction and the arrangement of parts associated therewith is usually further complicated due to the desirability or necessity of using a safety draw bar with the service draw bar. The result has been in certain prior constructions that an undue amount of space is required, particularly in modern locomotives where a great many flexible pipe and hose connections must be maintained leading from the locomotive to the tender and cars.

One object of our present draw bar arrangement is to take care of the necessary buffing and pulling stresses with a very strong draw bar construction and at the same time provide a relatively simple and compact arrangement for the safety or emergency draw bar.

In addition to the foregoing object and advantages, it is a further object to provide an improved relation between the draw bar and an emergency buffer whereby the draw bar is adapted to take the entire buffing or compression forces between the locomotive and tender and yet in the event of failure of the draw bar there will be no dangerous telescoping of the locomotive and tender. A further result is that in normal operation this improved arrangement provides a complete cover for the draw bar.

Other objects and advantages will be more apparent to those skilled in the art from the following description of the accompanying drawings in which:

Fig. 1 is a fragmentary elevational view of adjacent ends of a locomotive and its tender with

one form of our improved draw bar illustrated therewith;

Fig. 2 is an elevational view somewhat similar to that shown in Fig. 1 with parts broken away to show details of construction;

Fig. 3 is a plan view of the service draw bar per se;

Fig. 4 is a vertical transverse section taken on the line 4—4 of Fig. 2;

Fig. 5 is a vertical transverse section taken on the line 5—5 of Fig. 2;

Fig. 6 is a modification shown in elevation similar to Fig. 2;

Fig. 7 is a plan view of the modified service draw bar per se;

Fig. 8 is a transverse section taken on line 8—8 of the service bar;

Fig. 9 is a section of the ball;

Fig. 10 is a view showing one-half of a split ball socket.

In the illustrated embodiment of the invention, I have diagrammatically shown a locomotive 1 and its tender 2. The locomotive is provided with a usual frame terminating in a rear end plate or foot plate 3 and a draw bar pocket 4 while the tender is provided with a front end 5 and draw bar pocket 6. To provide a rigid connection between the locomotive and tender, a service draw bar indicated at 7 is provided at its ends with vertical cylindrical openings 8 and 9 to receive bushings 10 and 11 which as shown in Fig. 10 are diametrically divided to receive semi-spherical balls 12 and 13, each of which is provided with a vertical opening to snugly receive draw pins 14 and 15. The draw pins also project through and are journaled in opposed bearings 16, 17 and 16', 17' carried by the walls forming the draw bar pockets 4 and 6.

It will be noted that the rear end of the locomotive and front end of the tender each have a pair of downwardly projecting sides 18 and 19, Fig. 5, connected by a cross member 19' to provide an emergency draw bar pocket 20 while a still further transverse support 21 forms a keeper pocket 22. Each of the draw pins projects downwardly through a suitable bearing 23 and terminates in a reduced end to receive a keeper 24.

A safety or emergency draw bar 25 has enlarged ends provided to receive the draw pins 14 and 15 through holes 26 of only slightly larger diameter than that of the pins. Due to the rigid connection afforded by the service draw bar there is no necessity of having relatively large openings 26 in the emergency draw bar as is usual nor is it necessary to have oblong holes therein to permit usual slack in the service draw bar connection.

To afford the utmost strength in the service draw bar and yet permit a compact arrangement with the safety draw bar, we have constructed the service draw bar so that the safety bar may

pass within the confines thereof. To accomplish this the service bar in cross section is made of substantially U-form as shown in Fig. 4 having sides 27 and 28 connected by a top 29. It is usual to have the service bar of box shape in cross section as this affords the greatest possible strength. Hence in order to retain this strength and at the same time permit close cooperation between the safety and service bars, the normally lower wall of the box section is transformed into lateral flanges 30 and 31 with sufficient cross sectional area that the center of gravity about either the horizontal or vertical axes is substantially the same as in a box section. This arrangement thus provides an opening 32 in which the safety bar 25 is disposed to thus insure the utmost compactness of the unit. To give full strength to the service bar and also to limit the maximum vertical displacement of the safety bar, we have provided a pair of transverse ribs or webs 33 connecting the sides.

As a result of this construction it is seen that the bearings 8 and 9 lie nearer to a plane containing the top 29 of the service bar and in addition this arrangement permits the locomotive foot plate 3 to be considerably strengthened underneath as by having a rib 34 extend longitudinally from adjacent the bearings 16' to the head 35 of an emergency buffer, thereby considerably strengthening the buffer in addition to the strength afforded by an upper rib 36. Similarly a heavier or stronger construction is afforded for the front end 5 of the tender. The ends 5 and 6 carry independent radial buffer teeth or lips 37 to form an emergency buffer which will engage only upon failure of the draw bars, these buffers extending across a substantial portion of the front and rear ends of the locomotive and tender, thus affording ample cover for the draw bars. The arrangement of the draw bars, however, particularly as shown in Fig. 2 permits these buffers to be made of considerable strength and to be brought into close cooperating relation with the service bar. The toothed buffers may be detachably connected to, but preferably are integral with, the ends 3 and 5 of the locomotive and tender.

In the modification shown in Fig. 6 the service draw bar 40 has the same end bearing construction as in the preferred form although in Fig. 6 the bar is of the box type as shown in Fig. 8. The draw bar also tapers down above the top and under surfaces to the bearings at each end of the bar. The safety draw bar 41 is connected to the draw pins 42 and 43 in the manner described in the preferred form, although it will be noted that the rear end or foot plate 3' of the locomotive and the front end of the tender 5' are supported with under webs or flanges 44 of somewhat less depth and length than in the preferred form. In either modification, however, it will be noted that the rear and front ends of the locomotive and tender extend outwardly over the draw bars to within sufficient proximity to each other that they may effectively carry independent radial buffers having teeth 45 which extend across a substantial portion of the ends of the locomotive and tender and thus provide not only an adequate cover for the draw bars but also prevent telescoping of the locomotive and tender in case of accident.

From the foregoing description of the two modifications shown herein it is seen that we have provided a relatively simple arrangement whereby a rigid longitudinal connection may be main-

tained between the locomotive and tender and at the same time the service bar and safety bar are disposed immediately beneath the rear and front end plates of the locomotive and tender, these plates being so extended or otherwise constructed that they may be brought into close cooperating relation without normally touching each other. In one of the modifications we are also able to provide an extremely compact arrangement between the service and safety draw bar, thus affording more space in which may be carried the usual flexible hose and other connections leading from the locomotive, whereas in certain prior installations the connections might lie dangerously near cross over tracks or other obstructions in the trackway.

It will of course be understood that various changes may be made in the arrangement of elements and details thereof without departing from the spirit of the invention as set forth in the appended claims.

We claim:

1. The combination comprising a service draw bar having a hollow portion, means for pivotally connecting the respective ends thereof to a locomotive and its tender so as to maintain the same in longitudinal relation at all times, and a safety draw bar operatively connected with said locomotive and tender and extending within the hollow portion of said service draw bar.

2. The combination comprising a service draw bar having a hollow portion, means for pivotally connecting the respective ends thereof to a locomotive and its tender to hold the same in fixed longitudinal relation, and a safety draw bar operatively connected to the locomotive and its tender by a pivotal connection coaxial to the pivots of said service bar, said service bar being adapted to receive within its hollow portion at least a portion of said safety bar.

3. The combination comprising a service draw bar, means for pivotally connecting the respective ends thereof to a locomotive and its tender to hold the same in fixed longitudinal relation, and a safety draw bar operatively connected to the locomotive and its tender by a pivotal connection coaxial to the pivots of said service bar, said service and safety draw bars being disposed in superimposed relation and said service bar having a hollow portion to receive said safety bar.

4. The combination comprising a service draw bar having a longitudinal recess in one side thereof, connecting means at the ends of said bar, and a safety draw bar disposed in said longitudinal recess.

5. The combination comprising a service draw bar having a substantially U-shape cross section, and a safety draw bar disposed substantially parallel to said service bar and disposed in the open side of the U-shape service bar.

6. The combination comprising a service draw bar having pivotal supports at its ends and a relatively straight longitudinally extending top surface, said bar having a vertical dimension intermediate its length that is materially greater than at its ends and a hollow portion in said bar at said intermediate point, and a safety draw bar disposable in said hollow portion of said service bar at the point of its greatest vertical dimension.
